UNITED STATES PATENT OFFICE

149,526

DESIGN FOR A DOLL'S HEAD ORNAMENT
OR SIMILAR ARTICLE

Merle E. Taylor, Luckett, Va.

Application March 11, 1947, Serial No. 137,516

Term of patent 7 years

(Cl. D34—4)

To all whom it may concern:

Be it known that I, Merle E. Taylor, a citizen of the United States, residing at Luckett, in the county of Loudoun and State of Virginia, have invented a new, original, and ornamental Design for a Doll's Head Ornament or Similar Article, of which the following is a specification, reference being had to the accompanying drawing, forming part thereof.

I claim:

The ornamental design for a doll's head ornament or similar article as shown.

MERLE E. TAYLOR.
